UNITED STATES PATENT OFFICE.

LYNDON C. PALMER, OF BUFFALO, NEW YORK, ASSIGNOR TO THE F. N. BURT COMPANY
LIMITED, OF BUFFALO, NEW YORK, A CORPORATION.

GLUING APPARATUS.

1,033,266.

Specification of Letters Patent. Patented July 23, 1912.

Application filed December 27, 1910. Serial No. 599,382.

To all whom it may concern:

Be it known that I, LYNDON C. PALMER, a citizen of the United States, residing at Buffalo, in the county of Erie and State of New York, have invented certain new and useful Improvements in Gluing Apparatus, of which the following is a full, clear, and exact description, such as will enable others skilled in the art to which it appertains to make and use the same.

This invention has relation to gluing apparatus, and more especially to apparatus of such character which is used in applying glue to webs or strips of paper or similar material employed in the manufacture of paper boxes.

One object of the invention is the provision of an efficient apparatus for heating the glue.

Another object is the production of a practical apparatus wherewith a series or plurality of paper strips may be glued, thus facilitating rapid operation.

Another object is the provision of an efficient apparatus for heating a number of glue reservoirs from a single source of heat.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings in which similar reference characters refer to similar parts throughout the several views, Figure 1 is a plan view of the apparatus; Fig. 2 is an enlarged sectional view on line $\alpha-\alpha$ of Fig. 1; and Fig. 3 is an enlarged side view, partly in section.

In the manufacture of boxes, and especially in the operation of covering boxes with paper, a strip of the paper is placed around the sides of the box and attached thereto by glue or other suitable adhesive. By this invention the paper is held in position to be readily manipulated and also contiguous to a gluing device, so that the glue is applied to the paper as the paper is used in the covering operation; and a unitary system of heating the glue is provided for a series or plurality of gluing de-

vices whereby economy of heat, uniformity of glue, and saving of time are effected, besides other advantages which will be apparent from the detailed description.

Referring now in detail to the drawings, the numeral 1 indicates a table or horizontal support, on which is located the gluing apparatus, which comprises a series of heating devices or horizontal plates 2, spaced apart as desired. Each plate is preferably elevated above the table surface by legs 3 and supports a removable glue reservoir or tank 4, which rests thereon and is held from lateral displacement by lugs 5 on said plate, between which lugs the tank rests. Each supporting plate 2 has a preferably solid horizontal or body portion and an intermediate depending chambered or channeled portion 6 providing a passageway 7. The passageways in the plates are joined or connected by horizontal pipes 8 removably secured in place, and to one end plate of the series of plates is connected a pipe 9 having a hand operated cut off valve 10. From the other end plate of the series leads a pipe 11 having also a cut off valve 12. By means of this construction the passageways in the several plates are connected in series by the pipes 8 and a suitable medium, preferably steam, from a conveniently located boiler, is circulated through the passageways in the pipes to furnish heat for the glue.

The glue reservoirs or tanks 4 rest on the surface of the plates 2, respectively, and the plates serve as heaters to melt or soften the glue. Glue feeding rollers 13 dip into the glue in the tanks, respectively, and are preferably journaled on brackets 14 on the side walls of the tank.

Opposite one end of each tank is located a web supporting roller 15 preferably journaled in brackets 16 secured to the underside of each plate 2, and curved upwardly to properly position and accommodate a roll of the material to be glued, in this instance a paper web or "strip." On one side of the glue roller is located a guide roller 17 and on the other side a guiding and tension device comprising two rollers 18 and 19. These rollers are so disposed that when the web is passed therearound in the manner intended and over the glue roller, it will be drawn over and in contact with the glue

roller as the web is drawn from the supply on the roller 15. Preferably the rollers 17 and 18 are mounted in brackets on the side walls of the tank and the roller 19 is mounted between arms 20 pivoted concentrically to the roller 18 and adjustable around the roller 19, being adapted to be secured in adjusted position by nuts 21. The web is led from the supply roll beneath the guide roller 17, over the glue roller 13 and between the rollers 18 and 19, thence to the point of use. As the web is drawn off in use it is drawn across and in contact with the glue roller and glue is applied thereto, and as the glued web passes between the rollers 18 and 19 an amount of glue is wiped off, depending upon the position of the roller 19. Furthermore, the bight of the web where it engages the rollers 18 and 19 tends to tension it more or less, thus permitting the outer end 22 of the web to be cut off and left hanging without danger of unthreading from the gluing apparatus.

The pipes 8, between the glue tanks, are screened so as to prevent accidental contact therewith by removable covers or hoods 23 comprising substantially semi-circular walls having supporting flanges 24 resting on the table 1.

30 By the above described construction the glue reservoirs may be heated from a single source, thus economizing material and labor; individual glue tanks may be readily removed and replaced without interfering with the operation of others, thus facilitating refilling and repair, and the combination as a whole provides a gluing apparatus capable of indefinite extension, and at the same time one that is eminently clean and free from objectionable features usually present in apparatus working with glue, an especially desirable result when working with paper and on articles the appearance of which is of material consideration.

45 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention, which, as a matter of language, might be said to fall there-

60 between.

Having described my invention, what I claim as new and desire to secure by Letters Patent is:

1. In an apparatus of the character de-

65 scribed, in combination, a series of support-

ing plates, a series of glue reservoirs removably mounted thereon, said plates having chambered portions in their lower parts through which a heating medium is adapted to pass, pipes connecting said chambered portion, and valves adapted to control the flow of the heating medium through said chambered portion.

2. In an apparatus of the character described, in combination, a series of supporting plates, a series of glue reservoirs thereon, respectively, said plates having a solid portion and a chambered portion, pipes connecting the chambered portion of the plates for the supply of a heating medium, and means adapted to control the supply of heating medium to said chambers.

3. In an apparatus of the character described, in combination, a series of supporting plates, a series of glue reservoirs thereon, respectively, said plates having a solid portion and a chambered portion, pipes connecting the chambered portion of the plates for the supply of a heating medium, means adapted to control the supply of heating medium to said chambers, and removable hoods adapted to screen said pipes.

4. In an apparatus of the character described, in combination, a supporting and heating plate, a removable glue reservoir thereon, a glue feed roller journaled on the reservoir, guide rollers also journaled thereon and comprising a pair of tension rollers rotatively adjustable relatively to each other, between which a web is adapted to pass after being glued, and a bracket secured to the plate and adapted to support a web.

5. In an apparatus of the character described, in combination, a web supply, a glue roller, means to guide and hold the web into contact with the roller comprising two independently movable rollers between which the web is adapted to pass, and means to rotatively adjust the position of one of the latter rollers with respect to the other.

6. In an apparatus of the character described, in combination, a series of supporting and heating plates, a removable glue reservoir on each plate, a glue feed roller journaled on each reservoir, guide rollers journaled on each reservoir and comprising a pair of tension rollers rotatively adjustable relatively to each other between which a web is adapted to pass after being glued, and a bracket secured to each plate and adapted to support a web.

7. In an apparatus of the character described, in combination, a supporting plate, a glue reservoir thereon, a bracket secured to the plate and adapted to support a web supply, a glue roller supported by the reservoir, means to guide and hold the web in contact with the glue roller, comprising a plurality of independently rotatable rollers between which the web is adapted to pass,

and means to rotatively adjust the axis of one of the guide rollers with respect to the other.

8. In an apparatus of the character described, in combination, a glue reservoir, a glue feed roller, means adapted to support a web supply at one side of the feed roller, guides adapted to aline the web with the supply roller, comprising tension rollers disposed to receive the web therebetween after it is glued, and form a bight in the web to thereby restrain the free end of the web from unthreading.

9. In an apparatus of the character de-

scribed, in combination, a glue reservoir, a 15 glue feed roller, means adapted to support an endless supply of web, guides disposed to contact the web on opposite sides of the point of contact of the web and feed roller, and means adapted to normally positively 20 hold the web in contact with the feed roller.

In testimony whereof I affix my signature, in the presence of two witnesses.

LYNDON C. PALMER.
